SHEAVE BLOCK WITH ADJUSTABLE EYE

Robert Y Barkley, Weems, Va.

Application September 11, 1950, Serial No. 184,317

7 Claims. (Cl. 254—195)

1

This invention relates to sheave blocks, and more particularly to an improved form of sheave block adapted to control and limit the swing of the block in all directions both by means of the shape of the loop or bight of the block and in connection with the securing eye by means of which the block is attached to the boat or other object with which the device is to be used, and which will force the rope on to the sheave no matter from what direction the pull is exerted.

An object of the invention is to provide an improved sheave block and securing eye by means of which the sheave block is provided with a variable adjustable limit on its movement within the eye, selectively restricting such movement if desired to one side or the other of the eye as may be desired, and also restricting the passage of the bight through the variable adjustment limit of the eye by means of the fixed stop 7 and the adjustable stops 7', with a view to so disposing the block as to facilitate passage of the rope or cable through the bight in the block and thus eliminate any disposition of the rope to entangle itself with the block as the direction of pull may change.

A further object of the invention is to provide an improved and simplified structure for a sheave block by which the device can be constructed from stamped sheet metal or other suitable material without the loss of either strength or efficiency but at greatly reduced cost.

Various other objects will more particularly appear in the course of the following detailed description.

The invention consists in the novel construction, arrangement and combinations of parts hereinafter more particularly described and claimed.

One sheet of drawings accompanies this specification as part thereof, in which like reference characters indicate like parts throughout.

In the drawings:

Figure 1 is a side view of my improved sheave block and attaching eye bolt;

Figure 2 is a front elevation of the sheave block and attachment eye;

Figure 3 is a fragmentary cross section taken on line 3—3 of Figure 1;

Figure 4 is a transverse cross section taken on line 4—4 of Figure 2;

Figure 5 is an inner plan view of one of the stroke adjustment members showing details of its construction;

Figure 6 is a side view of the attachment eye 55

2

showing the adjustment plates adjusted to allow the maximum throw to the sheave block; and

Figure 7 is a side view of the attachment eye 5 with the adjustment plates adjusted to restrict the throw of the sheave block to one side or the other of the eye, as may be desired.

In my prior Patent No. 2,453,357, granted November 9, 1948, I have disclosed an improved sheave block in which the movements of the block with respect to the tethering eye are limited so that the block cannot fall or turn relative to the eye when the rope becomes slack and various other advantages are obtained.

15 The present invention is directed to an improved sheave block and eye by which the advantages of my prior block are retained and means are provided for selectively adjusting the throw of the block with respect to the tethering eye and in the vertical plane thereto, as may be desired under particular circumstances, and the entire device can be constructed with much greater economy and efficiency.

20 In the present invention the sheave 1 is pivoted as by a bolt 2 between the ends of the block frame which is constructed of an outer strap 4 and two inner plates 3, superposed one upon the other. The inner plates 3 will preferably conform to the shape and size of the sheave 1 and diminish in width toward their lower ends at which point they are provided with outwardly directed wings 7 adapted to be folded outwardly over the outer strap 4 at about points 5—5 on either side of the bight of the strap 4. Preferably the plates 3 will be rolled outwardly to eliminate undue friction on the rope. The bight portion of the strap 4 between the points 5—5 is embossed with a longitudinally extending outwardly concave groove 6 providing a convex transversely rounded inner face 8 providing a smooth contacting surface engaged by the inner circumferential face of the tethering eye 10.

25 It will be apparent that the groove 6 will further materially stiffen the strap 4 throughout the bight area of the strap. The wings 7—7 constitute fixed stops for the swing of the bight of the block through the tethering eye slot 20 and additional stops 7'—7' formed by screws positioned selectively in spaced threaded holes 9 formed in the bight may be used or additional stop lugs may be welded or otherwise secured to the bight.

30 The tethering eye 10, as illustrated, is provided with the conventional stem 12 threaded at its free end, as at 17, for securing purposes and is

35

formed on its opposed outer faces with transverse serrations 11. Obviously, other means for securing the eye may be used, as desired. Associated with the tethering eye are two adjustment plates 13 each comprising a centrally positioned, substantially circular part provided with a central screw-receiving orifice 15, and with a radially disposed segment 14 within which is stamped an arcuate groove 18 provided with transverse serrations adapted to engage and be held by the transverse serrations on the tethering eye 10 at selected positions. The two adjustment plates 13 are complementary and identical in structure and are secured with respect to the tethering eye 10 by the screws 16 which passes freely through one of these plates and is screw-threaded into the other, as illustrated in Figure 4.

It will be apparent from a consideration of the drawing that by loosening the screw 16 the adjustment plates can be angularly adjusted with respect to each other, thus increasing or decreasing the length of the arcuate slot 20 formed between the inner face of the tethering eye and the circular outer edge of the central portions 13 of the adjustment plates. It will further be observed that by providing the limited arcuate slot 20 and the transversely curved shape of the bight portion of the block strap 4, the turning moment of the sheave block strap 4 is limited by the width of this arcuate slot 20, providing a full equivalent to the slot and feather utilized in my previous construction, so that my improved sheave block and tethering eye with the latter's adjustment plates provides for selectively limiting the swivelling movement of the sheave block with respect to the tethering eye both in the plane of the tethering eye and in directions perpendicular with respect to the plane of the tethering eye, and the extent of the swivelling of the sheave block with respect to the tethering eye is adjustable both as to extent and as to its location with respect to the tethering eye.

Various modifications of the precise shape and construction of the parts will readily suggest themselves to those skilled in the art, but within the scope of the present invention as claimed.

Having thus described my invention, I claim:

1. Tethering eye for a sheave block having its opposite side faces roughened to provide frictional surfaces, adjustment plates complementary in size and shape, each of a width to cover a minor angular portion of the eye and formed on one face with a roughened groove to engage a portion of the roughened face of the eye and with a centering orifice, and screw means for engaging said plates through said centering orifices centrally of the tethering eye, whereby said plates can be angularly adjusted with respect to each other thereby modifying the length and position of an arcuate passage defined between the edges of said plates and the inner edge of the tethering eye.

2. Tethering eye for a sheave block comprising a ring member having tangentially secured fastening means for attaching the ring to a fixed member, two adjustment plates each of a width to cover a minor arcuate portion only of the ring, each plate formed on one face adjacent one end with a transversely disposed arcuate groove conforming in curvature with the ring and adjacent the other end with an orifice, said orifice constituting the center for said arcuate groove and means for securing said plates through said superposed orifices with the plates engaging opposite faces of the ring.

3. In combination a sheave block comprising a strap bent into loop form, a sheave rotatably mounted between the end portions of the strap, side plates positioned one on each side of the sheave adjacent the strap, each side plate shaped to conform in size and shape with the exposed part of the sheave and having a radial extension reaching to the side end of the bight portion of the loop, with oppositely disposed ears formed on the end of said extension folded to embrace the strap and constitute limit stops at the side ends of said bight portion, the strap formed throughout said bight portion with a longitudinal groove of concavo-convex cross-section with the convex side on the inside of said loop and a tethering eye slidable on the bight portion of the loops, between said stops, said eye having means for securing it to a fixed member and adjustable members defining with the inner edge of the eye an arcuate slot of adjustably variable length and angular location with respect to the eye within which slot the bight portion of the strap can slide in a circumferential direction with respect to said eye but can rotate in radial planes to only a limited degree determined by the width of the slot and width of the bight portion of the strap.

4. Sheave block comprising a strap in the form of a loop, a sheave rotatably mounted between the opposed ends of the strap, side plates proportioned and shaped to conform with and guard the sheave superposed on the ends of the strap with extensions converging in width to substantially adjacent the bight of the strap loop, with oppositely disposed lugs formed to embrace the strap at said terminal points, to constitute fixed stops at the ends of the bight portion of the strap, a tethering eye slidable on said bight portion between said stops, and auxiliary removable stops adapted to be adjustably secured to the bight portion of said strap within the range established by said fixed stops for shortening the range of sliding movement of said tethering eye along said bight portion.

5. Sheave block comprising a strap in the form of an open loop, said strap having an arcuate relatively wide bight portion and relatively narrowly spaced parallel end portions, and intermediate portions convergent from said bight portion to said end portions, a sheave rotatably mounted between said end portions, side plates interpositioned between said sheave and the end portions of said strap extending along the inner faces of the intermediate portions of said strap, having ends terminating in projecting collars about said strap at points intermediate the ends of said strap and the middle of said bight portion, forming stops, the bight portion of said strap being concavo-convex in cross-section between said stops with the convex side on the inside of said loop.

6. Sheave block as claimed in claim 5, said side plates being substantially congruent with the ends of said sheave, and convergent therefrom toward the intermediate portions of said strap, said ends of said side plates being secured by integral portions at said ends bent about said strap in clamping relation thereto, the opening in said loop from said bight portion to said sheave being pear shaped.

7. Sheave block comprising in combination, a loop shaped strap having opposed relatively narrowly spaced flat end portions in parallel planes, and a relatively wide bight portion rounded transversely on its inner side throughout an arc

extending to the opposite sides of said bight portion, a sheave rotatably mounted between said end portions, side plates interposed between said sheave and said end portions extending contiguous to said strap to the ends of the rounded arc of said bight portion and having lugs at their ends embracing said strap forming stops, a tethering eye slidable on the bight portion of said strap between said stops, said eye having its side faces formed with transverse serrations, complementary adjustment plates, each of said plates being formed with a centering orifice and each having a segmental portion formed with arcuate

transversely serrated grooves adapted to selectively and clampably engage various arcuate portions of the respective faces of the tethering eye, and screw means connecting said plates through said orifices whereby said segmental portions of said adjustment plates can be angularly adjusted to vary the limits of travel of said loop shaped strap with respect to said eye.
